UNITED STATES PATENT OFFICE.

JOHN J. CHAPIN, OF PORT WASHINGTON, NEW YORK, ASSIGNOR TO CHAPIN PRODUCTS CORPORATION, OF NEW YORK, N. Y., A CORPORATION OF NEW YORK.

CAN OPENER.

Application filed September 21, 1922, Serial No. 589,578. Renewed July 8, 1926.

This invention relates to certain new and useful improvements in can openers and has particular reference to that type of can openers capable of gripping the end of a can and opening or cutting the same without the necessity of actually gripping the can by the hands of the user of the device.

The primary object of the invention resides in the provision of a can opener in the form of a pair of pivoted lever arms that are struck from a blank of sheet metal and so bent and formed to provide gripping means for a rim or bead at one end of a can during the cutting operation on the end wall of the can.

The invention further provides in a can opener of the type above set forth, wherein the same is struck from sheet metal, the provision of gripping jaws associated with one of the handle levers that are struck out and bent into proper position from a sheet metal blank, reinforcing bent flanges or lugs being provided thereon while a cutter blade is removably anchored to the other handle lever.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a top plan view of a can opener constructed in accordance with the present invention, the same being illustrated as operatively positioned upon a can,

Figure 2 is a longitudinal sectional view taken on line II-II of Fig. 1 showing the cutter blades anchored to one of the handle levers and the guide stud pin positioned outwardly thereof,

Figure 3 is a longitudinal sectional view taken on line III-III of Fig. 1 showing the clamping jaws carried by the other handle lever for gripping the bead of the end wall of a can,

Figure 4 is a detail sectional view taken on line IV-IV of Fig. 1 showing the spacing rivets for the side walls of one of the handle levers and the guide pin associated with said rivets to prevent escape thereof,

Figure 5 is a detail sectional view taken

on line V-V of Fig. 1 showing the cutter 55 blade anchored in the handle lever,

Figure 6 is a detail sectional view taken on line VI-VI of Fig. 1 showing the pivot pins connecting the two sections of the other handle lever,

Figure 7 is a fragmentary perspective view of the inner end of the outer section of the handle gripping lever showing one of the gripping jaws carried thereby, and

Figure 8 is a perspective view of the inner section of the handle gripping lever showing the cooperating gripping jaw and the reinforcing spacing flange for the side walls of the handle section.

Referring more in detail to the accompanying drawing, there is illustrated a can opener embodying a pair of handle levers 1 and 2 pivoted together at adjacent ends by the rivet 3 as clearly shown in Fig. 1.

The can opener being constructed of sheet metal, the handle section 1 is formed from a blank bent to provide a substantially tubular gripping end 4, the other end thereof embodying spaced parallel side walls 5 that are maintained in spaced relation by the rivets 6 shown more clearly in Figs. 1 and 4. A guide pin 7 depends from one of the side walls 5 and is anchored to said side walls by the shank 8 carried by said pin, the end of the pin 7 adjacent the side wall 5 overlapping the adjacent end of the connecting rivet 6, while the end of the shank 8 extending through the opposite side wall 5 of the handle section 1 is swaged over the adjacent end of the connecting rivet 8 for permanently anchoring the same in position and properly bracing and spacing the side walls 5 of the handle section.

A cutter blade 9 is associated with the side walls 5 of the handle section 1, said blade carrying a shank 10 that extends through openings in the side walls 5, a wedge pin 11 extending through the blade shank 10 inwardly of the adjacent wall 5 for anchoring the cutter blade in the handle section, while the upper end of the blade shank 10 is shouldered as at 12 for wedgingly mounting the cutter blade and also bracing the side wall.

The handle lever 2 is formed of inner and outer sections 13 and 14 that are pivoted together by the pin 15, the outer section 14 constituting the gripping end that corre-

sponds to the portion 4 of the handle lever 1, while the pivoted end of the outer section 14 is bent to provide parallel side walls 16 shown more clearly in Figs. 6 to 8. One side wall 16 of the handle section 14 carries a depending flange constituting a gripping jaw 17. The inner section 13 of the handle lever 2 is bent to provide spaced side walls 18, one of said side walls carrying a depending flange forming a gripping jaw 19 that cooperates with the jaw 17, while the other wall 18 of the section 13 carries an angularly bent flange 20 engaging the opposite wall for properly spacing and bracing the section walls 18. The adjacent ends of the sections 13 and 14 carry ear projections 13^a and 14^a respectively, said ear projections being apertured for the reception of the pivot pin 15 as shown in Fig. 1. The pivotal connection 3 between the handle sections 1 and 2 embodies apertured ear extensions 1^a and 2^a carried by the handle levers 1 and 2 respectively that receive the pivot pin 3, while adjacent edges of the walls 5 and 18 are notched as at 21 to form an opening when the handle levers 1 and 2 are closed for hanging the device upon a support.

In the operation of the device, the same is positioned above the can C with the edge 30 rim or can bead B positioned between the jaws 17 and 19 of the handle lever 2 while the cutter blade 9 is forced into the upper end of said can adjacent the bead D. It will be noted that the guide pin 7 is positioned outwardly of the cutter blade 9 and when said blade enters the upper end of the can, the guide pin is positioned adjacent the outer wall thereof. Upon gripping the handle levers 1 and 2, the sections 13 and 40 14 of the handle lever 2 are moved on their pivotal connection 15 for closing the jaws 17 and 19 to grip the can bead B, and continued movement of the handle levers 1 and 2 toward each other will cause the cutter blade 9 to move through an arcuate path over the end wall of the can adjacent the bead B for opening the can. In actual practice, it frequently happens that the handle

lever 1 practically remains stationary while the handle lever 2 gripping the bead of the can will move the can relative to the cutter blade 9, the device operating for cutting a short incision in the end wall of the can, the handle lever 2 being then shifted to its fullest open position for again gripping the can bead for a similar operation.

While there is herein shown and described the preferred embodiment of the present invention, it is nevertheless to be understood that minor changes may be made therein without departing from the spirit and scope thereof as claimed.

What I claim is:—

1. A can opener comprising a lever formed of sheet metal having a substantially tubular handle portion merging into parallel side walls, a cutting knife passing through the parallel side walls, means for securing the cutting knife in place, a guide pin mounted in the side walls adjacent the cutting knife, a cooperating lever pivotally connected to the first mentioned lever and consisting of inner and outer sections each formed of sheet metal, the outer section having a tubular handle portion terminating in parallel side walls and with a flange projecting laterally from one of the walls, the inner section having parallel side walls with a cooperating flange projecting from the walls, means for pivotally connecting the two sections together, and means for pivotally connecting the two levers together.

2. A can opener comprising cooperating levers pivotally connected at one end, the levers consisting of sheet metal stampings bent into substantially U-shaped form and having the open sides facing one another, a cutting knife mounted in one of the levers, cooperating gripping flanges formed integrally with the second lever, the second lever having cooperating inner and outer pivoted sections to permit movement of the gripping flanges toward and from one another.

In testimony whereof I affix my signature.

JOHN J. CHAPIN.
